Attorneys.

UNITED STATES PATENT OFFICE.

RUSSELL LEE GORE, OF CARLISLE, KENTUCKY.

CHURN.

SPECIFICATION forming part of Letters Patent No. 325,530, dated September 1, 1885.

Application filed April 20, 1885. (No model.)

To all whom it may concern:

Be it known that I, RUSSELL L. GORE, a citizen of the United States, and a resident of Carlisle, in the county of Nicholas and State 5 of Kentucky, have invented certain new and useful Improvements in Churns; and I do hereby declare that the following is a full, clear, and exact description of the invention, which will enable others skilled in the art to which 10 it appertains to make and use the same, reference being had to the accompanying drawings, which form a part of this specification, and in which—

Figure 1 is a vertical transverse sectional 15 view of my improved churn. Fig. 2 is a perspective view of the dasher detached from the same. Fig. 3 is a detail view showing in perspective the several parts of the dasher separated or detached from each other; and Fig. 20 4 is a horizontal sectional view taken on the line $x-x$ in Fig. 1, with the ends of the dasher shown in horizontal section.

The same letters refer to the same parts in all the figures.

25 This invention relates to that class of churning which are known as "rotary churning," or which are provided with a revolving dasher and with means or mechanism for operating the same. The invention has for its object to 30 provide a device of this class which shall possess superior advantages in point of simplicity, durability, and general efficiency.

With these ends in view it consists especially in the improved construction of the dasher, 35 and of other component parts, as will be herein-after fully described, and particularly pointed out in the claim.

In the drawings hereto annexed, A designates a suitably-constructed box or receptacle, 40 which may be rectangular or of any other suitable shape, and which forms the cream-vessel of my improved churn. The said box is provided with detachable half-covers B', the inner or adjoining edges of which are 45 provided with suitable bearings for a detachable shaft, C, the construction of which will be herein-after more fully described. One of the said half-covers, B, is provided with a suitably-constructed upward-extending bracket, D, 50 having a bearing for a transverse shaft, E, carrying a gear-wheel, F, having a handle, G,

by means of which it may be conveniently manipulated. The said bracket D is also constructed with a downwardly-extending pindle, H, forming a bearing for the upper end 55 of the dasher stem or shaft C, as will be herein-after more fully set forth.

The shaft or stem C of the dasher consists of a tubular cylindrical stem provided at or near its upper end with vertical slots or openings I I for the admission of air, and with a ring or collar, J, having a laterally-extending vertical flange or groove, K, for the reception of a key or feather, L, formed upon one side of a detachable plug, M, adapted to be seated 65 in the upper end of the said tube, and retained in position by means of the said feather. The upper end of the said plug is formed or provided with a pinion, N, adapted to engage the gear-wheel F, as shown in the drawings. 70

O designates the dasher proper, which consists of a vertical tubular portion, P, adapted to be fitted upon the lower end of the dasher-staff C, and provided at its lower end with a transverse tubular brace, Q, which is elliptical 75 in cross-section, with sharp edges, and provided with open diagonal ends R R'. The said tube P is connected to the brace Q in such a manner as to admit of the passage of air from the one to and through the other, and the 80 underside of the tubular brace Q is provided with a centrally-located pindle or pivot pin, for which a bearing is formed in the bottom of the box or receptacle A, as shown.

Suitably-constructed wings or beaters R' R', 85 which may be formed of wire or of any other suitable material, connect the tube P with the transverse brace Q, as will be seen in the drawings. The construction of these beaters may be changed or modified to any desired 90 extent without departing from the spirit of my invention.

The operation and advantages of this invention will be readily understood from the foregoing description, taken in connection with the 95 drawings hereto annexed. When the dasher is revolved, which is done by means of the gear-wheel upon the churn-cover, the air will enter the upper end of the dasher-staff through the slots formed therein, and, descending 100 through the said hollow or tubular staff, will be emitted with considerable force through the

tubular brace at the lower end of the said staff and into the empty space or vacuum formed centrally in the body of cream by the revolution of the dasher.

5 By the general construction herein described the operation of churning is greatly accelerated and facilitated, and the butter product is gathered toward the center of the churn, and is, therefore, more easily removed from the

10 churn.

The dasher and its attachments may be easily and quickly removed from the churn and separated from each other, and each of the tubular parts may be readily cleaned

15 simply by passing a wet cloth through the part.

Having thus described my invention, I claim and desire to secure by Letters Patent of the United States—

In a rotary churn, the combination with a box or casing, of a vertical revolving tubular 20 stem or shaft, a plug inserted detachably in the upper end of the latter and having a pinion, a tube adjusted upon the lower end of said stem and having a transverse tubular brace and suitable wings or dashers, and suitable bearings and operating mechanism for the said stem or shaft, substantially as and for the purpose herein set forth.

In testimony that I claim the foregoing as my own I have hereunto affixed my signature 30 in presence of two witnesses.

RUSSELL LEE GORE.

Witnesses:

JOHN FREY,
GEORGE E. MOTCH.
